UNITED STATES PATENT OFFICE.

EMIL KRENZLER, OF BARMEN, GERMANY.

BRAIDING-MACHINE.

1,141,555.

Specification of Letters Patent.

Patented June 1, 1915.

Application filed June 9, 1914. Serial No. 843,972.

To all whom it may concern:

Be it known that I, EMIL KRENZLER, a subject of the German Emperor, residing at Barmen, Prussia, Germany, have invented 5 certain new and useful Improvements in Braiding-Machines, of which the following is a specification.

The object of the invention is a lace braiding machine, which, after the manner of the 10 known so-called "single-thread" braiding machines, *i. e.* braiding machines having one bobbin per plate is composed of a series of circular plates which are severally provided with an arrangement, actuated by 15 the pattern gear, for arresting the bobbins. While in the known machines of this kind each plate is constructed with two driving notches and provided with only two arresting positions arranged generally at the intersecting points of the track, according to 20 the present invention some or all of the plates are provided with four driving notches and have four arresting positions and are so connected with the pattern gear 25 that they can be actuated at every quarter revolution of the driver. It is thus attained that one can intertwist not only two braiding threads as hitherto, but two, three or four exactly as desired and thus quite new 30 patterns can be produced.

This improvement may be used on all single-thread braiding machines. It is however specially suitable for those machines in which the drivers, for the purpose 35 of arresting and reengaging the bobbins, are temporarily disconnected from or connected with the driving wheels, which revolve continuously, by means of a clutch actuated from the pattern gear.

40 One form of the invention, in which the plates act at the same time as drivers and switches are dispensed with, is represented by way of example in the drawing, wherein:

45 Figure 1 shows the arrangement of the plates in plan, Fig. 2 is a section on the line A—A of Fig. 1 in connection with the pattern cords, which are shown diagrammatically, Fig. 3 is a diagrammatic representation of a piece of lace manufactured by the 50 new machine.

55 Referring to the drawing, *a* is the upper track-plate of the machine and *b* are the braiding plates which are in known manner constructed at the same time as drivers by

cutting the slots *c* out of them. The drivers are revolvably mounted and each possesses a longitudinally adjustable clutch *d*, which is ordinarily held in the high position, *i. e.* out of gear, by the spring *h* by means of the 60 fork *g* fixed to a guide bolt *f*, and when required is lowered by the pull of the angle-lever *i*, which is actuated by the pattern gear and can thus be brought into gear with the continuously revolving driving-hub *k*. 65 The several plates are each provided with four slots *c* for the reception of a bobbin and at the upper edge of the clutch-sleeve *d* there are four slots *m* which engage with a stop *n* fixed to the machine and on disengaging 70 the clutch arrest the driver in exactly the right position. The draw-rod *i* is connected with the four lifters *p* by means of the four independent angle-levers *o*, which can be connected separately or in groups or 75 all together with the four knives *q* which come into action one after another once during each revolution, and correspond each to a quarter revolution of the driver. It thus becomes possible to let the individual plates 80 make one or more quarter revolutions as desired, and thus to pass over two, three or four bobbins as desired on to one plate in order to effect a twisting of their threads. Thus, for example, in the lace-pattern manu- 85 factured in this way and diagrammatically illustrated in Fig. 3 there are along the length I four threads intertwined twice, while along the length II there are three threads intertwined twice and two once. 90

On this new machine, two, three or four threads can be intertwined as desired, and therefore, in contradistinction to the former braiding machines with the intertwisting of two threads only is possible, quite new patterns can be produced. 95

What I claim as my invention and desire to secure by Letters Patent is:—

1. In a lace braiding machine, a rotary plate having four equidistant slots in its 100 peripheral part, in combination with a stop for said plate, a movable clutch member arranged below said plate and similarly provided with four slots which are individually adapted and arranged to receive said 105 stop when presented thereto, a yielding device adapted automatically to move said member into such locking position, a driving gear for said plate provided with a clutch member, and means actuated by a 110

pattern for shifting the former clutch member into operative engagement with the latter clutch member.

2. In a lace braiding machine, a rotary plate having four equidistant slots in its peripheral part, in combination with a stop for said plate, a movable clutch member similarly provided with an equal number of corresponding slots which are individually adapted 5 and arranged to receive said stop when presented thereto, means for moving said clutch member into engagement with said stop, a clutch member for driving said plate and automatic means for shifting the former 10 clutch member out of engagement with said stop and into engagement with the latter clutch member.

3. In a lace braiding machine, a series of rotary plates, each having four equidistant 20 slots in its peripheral part, in combination with a corresponding series of similarly slotted clutch members, a corresponding series of stops for said rotary plates adapted to engage them individually, a corresponding 25 series of clutch members for driving said plates and automatic means for shifting each of the former clutch members, as predetermined, out of engagement with its stop and into engagement with the corresponding clutch member of the other series.

4. In lace-braiding machines, a number 30 of rotary plates each adapted to act as a driver in any one of four positions, in combination with a corresponding series of clutch members adapted to engage stops in the same positions, a series of stops arranged for such engagement, a series of clutch members for driving said plates and means for shifting any one of the first series of clutch 35 members out of engagement with its stop.

and into engagement with the corresponding clutch member of the plate-driving series.

5. In lace-braiding machines, a rotary plate operative at four equidistant points of 45 its periphery, in combination with a rotating coupling member adapted for engagement at a corresponding number of points, a stop arranged to engage said member at such points, means for driving said plate, a coupling member governing said means, devices for shifting the former coupling member automatically out of engagement with said stop and into engagement with the second coupling member, four knives adapted 50 to move successively at the quarter revolutions of the first mentioned clutch member and means engaged by said knives for coupling and uncoupling this clutch member to and from said plate.

6. In lace-braiding machines, a rotary plate having four equidistant slots in its periphery, a rotating clutch member, and four knives adapted to move successively at the quarter revolutions of said member, in 60 combination with automatic means comprising lifters, each of which is arranged to engage one or more of the said knives at will and to be disengaged therefrom for coupling and uncoupling the said plate to and from the said clutch member and means for yieldingly holding the said plate in any one of its four positions.

In testimony whereof, I have signed my name to this specification in the presence of 75 two subscribing witnesses.

EMIL KRENZLER. [l.s.]
